UNITED STATES PATENT OFFICE.

ALEXANDER K. SUTHERLAND, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

PUSH-BUTTON SWITCH.

1,268,804.

Specification of Letters Patent. Patented June 4, 1918.

Application filed April 24, 1915. Serial No. 23,655.

To all whom it may concern:

Be it known that I, ALEXANDER K. SUTHERLAND, a citizen of the United States, and a resident of Plainville, in the county of 5 Fairfield and State of Connecticut, have invented certain new and useful Improvements in Push-Button Switches, of which the following is a full, clear, and exact description, whereby any one skilled in the art may make 10 and use the same.

The invention relates to electric switches and more particularly to a push button switch or any type of switch in which the contacting parts are normally held in a 15 locked position and released by a moving element to provide a quick make and break of the contact members. In devices of this character, it has been a common practice to employ a moving switch blade which blade 20 is placed under a spring tension by the movement of the actuating buttons. The blade is normally locked, until it is fully under tension, through a suitable detent and the detent is then moved to release the blade, 25 permitting it to move very rapidly under its tension. Various mechanisms have been provided for effecting a release of the detent.

In a co-pending application, Serial No. 30 9793, filed February 23rd, 1915, I have illustrated a mechanism for releasing the detent in which during a nominal movement of the actuator, an amplified or multiplied movement is imparted to effect the release of the 35 detent or locking elements. In such devices, accuracy is required to insure proper operation of the releasing mechanism and detents, particularly after the switch has been in service. Great difficulty has been experienced in maintaining sufficient accuracy 40 and permitting ready assembly. In constant use, to which such devices are subjected, it is not an unusual circumstance for the camming member to "hang up". That 45 is, to bind or stick during its movement so that a complete movement thereof is not effected after the detent has been released and at which time, the camming member should be thrown over to its extreme position, ready 50 for a new movement.

The present invention has to do with a mechanism which overcomes such a difficulty and while analogous to the improvement shown and described in the prior applica-

tion above referred to, embodies additional 55 features of surety in operation which assure a positive positioning of the releasing cam member at every movement of the parts.

The object of the invention is to provide 60 a switch having a detent and a releasing device therefor, which is actuated both by the depression of the operating buttons and mechanism and is further subjected to direct operation by a movement of the switch 65 blade itself.

It is also an object of the invention to provide a simple device with features of easy 70 assembly and manufacture, which require no bending or adjusting during assembly, which will prevent perfect operation during the life of the switch.

A still further object is to amplify a given movement from the actuating bar of the switch with reference to the detent, providing a minimum of friction, a maximum of movement and finally to subject the actuating device for the detent to the direct and final blow of the switch bar during its movements and while under tension. 80

Referring to the drawings:

Figure 1 is a longitudinal sectional view through the switch.

Fig. 2 is a cross-sectional view on the line 2-2 of Fig. 1. 85

Fig. 3 is a diagrammatic view illustrating the parts of the switch mechanism with the left-hand button partially depressed, the contact blade being removed.

Fig. 4 illustrates the position of the parts 90 as the release takes place between the detent and with the detent actuator at the central position of its movement.

Fig. 5 is a similar diagrammatic view 95 illustrating the detent actuator at the extreme opposite limit of its play as compared with Fig. 3.

Fig. 6 is a perspective view of the unassembled parts and their relative position for assembly. 100

As already indicated, it is not new in the art to provide an oscillatory switch blade member and an oscillatory actuating member for tensioning the same with a detent for holding the switch blade member during 105 the tensioning action of the actuator. Neither is it new to provide a detent which will be released upon substantially full ten-

sioning movements of the actuator so that the switch bar will make and break its connections with the contacts instantaneously.

In devices of the prior art, so far as known, no special provision has been made for giving what is substantially a double action in the mechanism for moving the detent. That is, such a movement or action as will normally raise the detent out of engagement with the stop or other device connecting with the switch blade and will, when in raised position, give a positive movement thereto for precluding the possibility of improper throw.

As hereinafter described, the present invention provides, through a cam action, for moving the detent, to permit a release of the tensioned switch blade and upon release of the switch blade under tension, the cam is forcibly and positively knocked into its extreme position ready for a reverse movement of the switch blade. This mechanism precludes the possibility of the cam mechanism or detent actuator "hanging up" or stopping in a position intermediate its intended full length of throw. Much of the detail of the mechanism of a snap switch is well known in the art and needs no detail description.

Referring to the drawings, the numeral 1 denotes the insulating receptacle within which are inclosed and suitably mounted the various parts of the mechanism.

The stationary contacts are illustrated at 2, 3 and may be of any desired and approved form. Fitting across the upper portion of the receptacle 1, there is a frame member 4, provided with perforations through which the push buttons 6, 7 project and by which they are guided. This frame 4 has dependent members 8, 9 formed integrally therewith and both of these members are slotted or perforated as at 10, 11 to receive and hold a detent 12.

This detent is best shown in the detail of Fig. 6 and consists of a blanked-up bar, one end 13 of which projects through the slot 11 and serves as a stop or detent for the switch blade. The rear end has a shoulder 14 which passes through the perforation 10 of the plate 8 and prevents dislodgment of the bar 12 when the parts are assembled. Overlying the detent bar 12 is a U-shaped spring 15, the upper portion of which has a projecting tang 16 which may be inserted in the slot 11 and with its lower arm 17 resting upon a depressed portion 18 of the bar 12 and against a shoulder 19. This arrangement of spring and bar forms an interlocking arrangement which will prevent dislodgment of any of the parts when once assembled. It also permits ready assembly of the parts.

At the lower end of the dependent frame members 8, 9, are stop shoulders 20 which

limit the movement of the contact blade yoke 21. This yoke 21 embraces the two dependent portions 8, 9 of the frame and is pivoted thereto by a pin 22 passing through perforations 23. The yoke member 21 has an upwardly extending arc-shaped arm 24 which cooperates with the detent bar 12 to hold the yoke in locked position at either limit of its play.

Arranged between the dependent arms 8 and 9 and pivoted upon the pin 22 is an actuator bar 25 having a spring barrel 26, two-arm spring 27 and lug 28 projecting between the two arms of the spring. The two arms of the spring 27 straddle the connecting bar of the yoke 21 so that when the yoke member is held against movement by the arm 24, and detent bar 12, movement of the actuating bar 25 will place the yoke under tension of the spring 27.

Projecting from the upper portion of the actuator bar 25 are lugs 29, 30 which are arranged to engage and move the detent actuator 31.

This actuator 31 is pivotally mounted on the pin 22 just inside the frame member 9 and bears flatly against it. At its upper end, it is provided with two depressions 32, 33 and intermediate these depressions is a cam surface 34. When the actuator 31 is at either limit of its play, the detent bar 12 rests in one of the depressions 32 or 33 and when in this position, the arm 24 is locked against movement on one side or the other of the detent bar.

When the detent actuator 31 is moved, through an engagement with either of the lugs 29, 30 of the actuator 25, it is swung on its pivot, carrying the cam 34 under the detent bar and raising the same to free the arm 24 of the switch yoke 21.

During the movement of the actuator bar to effect this movement of the detent actuator 31, the spring 27 has been placed under tension and the switch yoke and its blade are likewise under tension.

The lower end of the detent actuator 31 is of circular form as at 35, conforming to the arc of movement of the yoke 21 which passes about the lower end 35 of the detent actuator 31.

At either end of the arc 35 are shoulders 36, 37 and these are so spaced with reference to the depressions 32, 33 and cam 34 that the yoke member 21 will sharply impinge against one or the other of the shoulders as soon as it is released for a free movement under tension of its spring as by the raising of the detent bar 12. In other words, when the cam 34, at its highest point, is just underlying the detent bar, which is raised to effect a release between said bar and the stop arm 24, one of the shoulders 36, 37 will be within the arc of movement of the yoke 21. As the yoke 21 moves instantaneously under

the tension of the spring at this position of the parts, it will assuredly strike the shoulder of the detent actuator 31 and forcibly move it into its extreme position.

5 It will be observed from this construction that where heretofore cams have been relied upon for moving the detent, the present device provides a secondary means for moving the detent actuator. This positively insures 10 positioning of said actuator with the detent in proper position to positively hold the yoke bar 21 against movement. The diagrams in Figs. 3 to 5 clearly show this operation.

It is of course to be understood that the 15 exact shape, detail and arrangement of the various parts of the mechanism might be varied to suit the exigencies of any particular case, provided there is an actuating device for the detent member and a secondary 20 actuating device for insuring a definite setting of the detent actuator.

What I claim as my invention and desire to secure by Letters Patent is:

1. In a device of the character described, 25 a support, an oscillatory switch blade, an actuator for tensioning and moving the same, a detent, a detent actuator for freeing said detent, means for initially moving said detent actuator upon movement of the 30 switch actuator to fully release the parts for flying movement of the switch blade, means moving with the switch blade in its free flying movement for impinging against and imparting by impact therewith final 35 movement to said detent actuator.

2. In a device of the character described, a support, an oscillatory switch blade, an actuator bar resiliently connected therewith for tensioning and moving said switch blade, 40 means for moving said bar, a detent for holding said switch blade against movement and means for moving and releasing said detent whereby the switch blade may move, comprising a movable member and 45 means upon the actuator bar for engaging and imparting an initial releasing movement thereto and means upon the switch blade for imparting final movement thereto by impact therewith.

50 3. In a push button switch, a supporting frame having dependent supporting members, an oscillatory switch blade pivotally mounted in said dependent members, an actuator bar and push buttons, resilient connections intermediate said actuator bar and switch blade for tensioning and moving the latter, a detent arm connected with the switch blade, a detent projecting through the dependent members and locking the 55 detent arm against movement, an oscillatory pivoted cam plate for moving said detent to release the detent arm and the switch blade, means upon the actuator bar for imparting partial oscillatory movement to 60 the cam plate to release the switch blade under tension, and means connected with the switch blade for striking said cam plate to complete its oscillation.

4. In a push button switch, a supporting frame having dependent members, a switch 70 blade yoke bearing a switch blade, a detent member, said yoke and detent member pivotally mounted to oscillate in the frame, an actuator bar for actuating the switch blade, a pivoted cam plate adapted to be moved directly by the actuator bar during the partial movement of said actuator, a detent extending through the dependent members and having one end resting upon the cam plate, resilient means for depressing said 75 detent member against the cam and abutments upon said cam plate adapted to be engaged by the oscillatory switch blade yoke as said yoke is released.

5. In a push button switch embodying a 80 supporting frame, oscillatory switch blade, actuator bar and means for moving the switch blade upon movement of the actuator bar, of a detent bar extending through oppositely disposed perforations in the supporting frame, said bar having a spring seat and a shoulder engaged by one end of a spring and a U-shaped spring having one end projecting into the perforation of the frame and its opposite end resting 85 against the shoulder of the detent, whereby said detent is held in operative position in the frame, and a cam plate for moving said detent to release the switch blade upon 90 movement of the actuator bar.

6. In a push button switch, a supporting frame, an oscillatory switch blade having a yoke and a detent arm, a detent bar loosely supported in perforations in the frame and projecting into the path of movement 105 of the detent arm, a pivoted oscillatory cam plate having a cam surface at one end for moving the detent bar and having at its opposite end shoulders adapted to be engaged by the yoke of the switch after disengagement of the detent and detent arm and release of the switch blade and yoke whereby final movement is imparted to the cam plate, and means borne by the actuator bar for imparting an initial and releasing 110 movement to said cam plate.

7. In a push button switch, a supporting frame, an oscillatory switch blade having a yoke and a detent arm, a detent normally holding the blade against movement by engagement with the detent arm, a pivoted oscillatory cam plate having a cam surface for disengaging the detent bar and detent arm, and provided with stop shoulders limiting the movement of the oscillatory cam plate, 120 and provided with shoulders adapted to be engaged by the switch blade yoke as said yoke moves after the cam of the cam plate has disengaged the detent bar and detent arm, whereby a shoulder of the cam plate is 125 130

4
driven against the detent, and means for imparting an initial releasing movement to the oscillatory cam plate.

8. In a push button switch having an oscillatory switch blade, means for moving said switch blade, a detent device and releasing cam, a supporting frame for said parts having perforations, a detent bar extending through said perforations and having one end resting upon the releasing cam, a spring engaging the frame and engaging the detent bar, said spring locking the bar against transverse movement in the perforations of the frame.

15 9. In a push button switch having an oscillatory switch blade, means for moving

said switch blade, a detent device and releasing cam, a supporting frame for said parts having perforations for a detent bar, a detent bar extending through said perforations, said bar having a shoulder abutting against the frame and having a shoulder for engagement with a spring, and a spring engaging the frame at one end and with its opposite end engaging the spring shoulder of the detent bar, whereby said detent bar is held against longitudinal movement in the frame.

ALEXANDER K. SUTHERLAND.
